UNITED STATES PATENT OFFICE.

DAVIS W. ENTRIKIN, OF KENNETT SQUARE, PENNSYLVANIA.

HARVESTING-MACHINE.

SPECIFICATION forming part of Letters Patent No. 252,088, dated January 10, 1882.

Application filed November 16, 1881. (No model.)

To all whom it may concern:

Be it known that I, DAVIS W. ENTRIKIN, of Kennett Square, in the county of Chester and State of Pennsylvania, have invented certain new and useful Improvements in Harvesting-Machines, of which the following is a specification.

This invention relates to that class of harvesting-machines wherein the cut grain is received upon a moving endless apron, and is thereby conveyed sidewise across the machine and delivered to the elevator, which discharges it in suitable condition to be bound either by hand or automatically.

The objects of my improvements are to provide means to advance light or tangled grain that may fall upon the conveyer, or bring it into closer contact than heretofore with said conveyer, so that the latter will carry it steadily to the mouth of the elevator, as a great difficulty is often experienced with curly or flossy light grain that has not sufficient weight in it to press enough on the conveyer to be moved thereby, (as there is always some slight resistance caused by the stalks of said grain resting on the cutter-bar or the side of the conveyer-frame,) and other means are required besides the moving conveyer to cause it to reach the elevator.

Heretofore reciprocating rack bars placed in the rear of the cutter-bar to advance the butts of grain, as well as rakes and other similar devices pivoted to either side or to the rear of the frame of harvesters, have been used in connection with a stationary platform; but their operation is often objectionable, and that class of harvesters differs materially from those provided with endless aprons. Good results are obtained with the latter class of harvesters upon curly light grain by means of a device or moving lever nearly similar to the one shown in my Patent No. 247,182, of September 20, 1881; but while that device straightens the grain just before entering the elevator, in my last improvement the moving lever is made to oscillate over the conveyer in the same direction with its path, and consequently at about a right angle with the lever in said patent. I attain these objects by the mechanism illustrated in the accompanying drawings, in which—

Figure 1 represents a perspective of a harvester-frame to the rear beam of which my im-

provement is attached. Fig. 2 is a perspective view of a similar frame with the improved device secured to the driver's foot-board. Figs. 55 3 and 4 represent respectively a side view of the upper portion and a perspective of the lower portion of the grain-moving lever.

In said drawings, A represents the front or finger bar of the machine, and A' the rear beam. At the inner end of the machine the elevator-frame A² is placed, to carry, as usual, the pairs of rolls b and c, around which are stretched the elevating-aprons B and C; and the horizontal conveyer D is also mounted upon rolls 65 d, to which motion can be given in any convenient manner.

E represents the dividing-board, and F the driver's foot-board, upon the rear end of which the driver's seat is generally placed.

The above-mentioned parts are in common use; but the means to advance flossy light grain, consisting mainly in a slotted lever, I, connected with the frame and adapted to oscillate in a plane corresponding with the path of the conveyer, are brought into action as follows, as represented in Fig. 1:

Upon the rear beam, A', of the harvester-frame is adjustably secured a post, J³, having a horizontal arm, J², carrying at its extremity the standard J. This standard has on one side of its upper end a projection, J', made to extend over the pulley or crank wheel K, that gives motion to the lever I. The upper end of this lever is retained connected to the projection J' of the standard by a washer placed under the head of the screw j, passing through a longitudinal slot in the lever and screwed into or bolted to the projection J' of the standard. The pulley or crank wheel K is pivoted to the standard, and carries a headed crank-pin, k, that passes through the lever I and (in connection with the screw j in the slot i) causes the lower end to describe a long flat curve over and among the grain that may be upon the 95 conveyer. Motion to the crank-wheel K can be given by connecting the pulley k² upon its shaft with a pulley, C', upon the end of one of the rollers carrying the conveyer-aprons.

In Fig. 2 the lever I and its standard J are shown as connected with the driver's foot-board F by means of a horizontal arm, J². Said arm may be pivoted to said foot board upon the vertical shaft m, so as to adjust the

path of the lower end of the lever I as may be desired, according to the length of the grain-straw, and then be secured by a locking-pin, m' , passing through the arm J^2 and foot-board

5 F, the shaft m carrying two guide-pulleys, $n n$. Motion can be transmitted to the pulley K from the pulley L on the reel-shaft l ; but other well-known means may be used for operating the arm I, so that it will partly advance or press

10 the grain upon the conveyer.

In Fig. 1 there is shown an arm suspended from the top of the driver's foot-board; but it forms no part of this invention.

To render the lever I more yielding, I prefer 15 to connect it with the crank-pin k of the crank or pulley K by passing said pin through a yielding bearing, p , sustained by springs q in the lower slot, i^2 , of said lever; and to cause the lower end of the lever I to come at each 20 rotation in contact with a larger amount of grain upon the conveyer I provide said lever with a shoe, I^2 , pivoted thereto and adapted to yield by means of flat springs i' , and thus conform its path more closely to the plane surface

25 of the conveyer.

Having now fully described my invention, what I claim is—

1. The combination of the frame and movable conveyer of a harvester with a movable

30 arm or slotted lever suspended over said conveyer, and operating mechanism to cause it to advance or press the grain upon said conveyer in the direction of the path of the latter, substantially as and for the purpose described.

2. The combination of the conveyer, the elevator, the foot-board of a harvester, and the horizontal arm J^2 , with a standard upon the end of said arm, a pulley provided with a crank-pin, and a slotted lever adapted to sweep over the conveyer in the direction of the path of the 40 latter, substantially as and for the purpose described.

3. The combination of the frame and conveyer of a harvester with a slotted lever provided with a yielding bearing, p , a crank, and 45 operating mechanism, substantially as and for the purpose described.

4. The combination of the frame and conveyer of a harvester with a crank, a slotted lever adapted to swing over said conveyer, and 50 a shoe, I^2 , pivoted to the lower end of said lever, substantially as and for the purpose described.
